UNITED STATES PATENT OFFICE.

STUART W. CRAMER AND WILLIAM B. HODGE, OF CHARLOTTE, NORTH CAROLINA;
SAID HODGE ASSIGNOR TO SAID CRAMER.

METHOD OF MAKING SPRAY-NOZZLES.

1,028,812.

Specification of Letters Patent.

Patented June 4, 1912.

Application filed October 26, 1910. Serial No. 589,199.

To all whom it may concern:

Be it known that we, STUART W. CRAMER and WILLIAM B. Hodge, citizens of the United States, residing at Charlotte, in the county of Mecklenburg and State of North Carolina, have invented certain new and useful Improvements in Methods of Making Spray-Nozzles; and we do hereby declare the following to be a full, clear, and exact 10 description of the invention, such as will enable others skilled in the art to which it appertains to make and use the same.

Our invention relates primarily to humidifiers for moistening the air in mills, 15 factories and other buildings and has especial reference to water spray-nozzles.

The particular form of spray-nozzle to which our invention refers, and to which it is applicable, is that consisting of a body- 20 member arranged for attaching to a supply pipe, a jet discharge orifice either incorporated directly into the body part or into a detachable member adjustably secured thereto, and a pillar upon which is sup- 25 ported a jet breaking up pin, opposite to and concentrically arranged with reference to the discharge orifice.

The object of the invention is to secure great accuracy in centering the orifice in 30 line with its breaking up pin, as well as increasing the durability of the device, and the invention consists in certain improvements, which will be fully disclosed in the following specification and claims.

In the accompanying drawings, which 35 form part of this specification:—Figure 1 represents a sectional view of the nozzle with the pin and bushing arranged for casting. Fig. 2 is a like view of a completed nozzle 40 ready for use. And Fig. 3 represents a longitudinal section of a mold for casting the nozzle.

Reference being had to the drawings and the designating characters thereon, the nu- 45 meral 1 indicates the nozzle-frame or yoke, cast of suitable metal as part of the body 6. The frame or yoke supports the pillar 5 in which is inserted a pin 4, opposite and di- 50 rectly under the orifice 7, through which water is discharged. The body is provided with a screw-thread 2, by which it is at- 55 tached to a pipe, not shown, for conveying water to be sprayed.

In constructing nozzles heretofore, it has 55 been the common practice to attempt to get

the pin 4, Fig. 2, opposite the opening or orifice 7 by mere mechanical methods. Owing to the fact that the accurate centering of this pin exactly opposite and in alignment with the orifice almost solely deter- 60 mines the efficiency of the nozzle, that is, the ability to divide the water up in extremely fine spray, numerous methods have been used to get this centering perfect. Inasmuch as the diameter of the pin 4 is usu- 65 ally slightly greater than that of the orifice 7 through the bushing 3, the proper and permanent mechanical centering of the pin with the orifice is extremely difficult. If these are cast in, the inability to hold the 70 pin 4, Fig. 2, perfectly rigid during the contraction of the metal renders it likely to spring one way or the other, and when the casting is finally cool it is not axial with the nozzle orifice. In previous types of nozzles, 75 the orifices have been in the metal of the casting itself. In other words, a hole drilled through the casting to form the orifice at the proper point opposite the pin. An objectionable feature of this construction is 80 that the water passing through at high velocity wire draws the sides of the orifice, this is on account of the fact that the metal used in casting is not uniformly hard and homogeneous. To overcome this grooving 85 action, and to aid in centering the pin, we have arranged the bushing 3, Fig. 1, in connection with the pin 4 to be held each by the other in their respective positions, and the metal of the nozzle body cast around 90 them while they are thus held rigidly. The bushing and the pin become homogeneous with the body and both are permanently embedded therein. It is advisable to have the pin 4 as shown in Fig. 2 slightly larger 95 in diameter than the orifice of the bushing 3. On this account the pin 4 is made with two diameters, the smaller diameter exactly the same as the inside diameter of the orifice in the bushing, whereas the larger diameter of the pin 4 is of the proper size to break up the stream of water to the best 100 advantage. The bushing and pin are made of tough metal, such as nickel, whose melting point is higher than the melting point 105 of the metal of which the body is made and is therefore better adapted to resist the erosive action of the water at high velocity.

The bushing 3 is slipped on the smaller end of the pin 4 with a tight fit, as shown 110

in Fig. 1, which holds it axially central with the pin. The casting is then made and finally the end of the pin which extends from the lower end of the bushing is filed off, 5 leaving the proper space between the lower end of the bushing and the upper end of the pin to get the desired water breaking effect. Owing to the fact that the pin and the bushing have been held axially while the 10 molten metal was poured around them and allowed to cool, it can be readily seen that these two parts are exactly in line with each other, and after filing off the end of the pin and removing the part in the orifice, the 15 stream of water issuing from the orifice of the bushing 3 will strike the upper end of the pin 4 exactly central and result in a uniform spray of water surrounding pin 4.

The mold shown in Fig. 3 comprises a 20 three part flask consisting of the drag 8, the cope 9 and the cheek-piece 10, the cope and the drag being provided with the usual dowel-pins, not shown, and the cheek-piece secured thereto by screw-bolts 11. The bushing 3 is supported in the boss or projection 12 on the cheek-piece 10 and the pin 4 is supported in the drag 8, with one end extending into the bushing, as shown. The boss or projection 12 is exteriorly screw- 25 threaded at 13 to form the screw thread in the body 6.

It is of course possible to use pins and 30

bushings of any desired material so as to resist corrosion and wear and of any desired ratio between the diameter of the orifice and 35 the diameter of the pin.

The spray nozzle forms subject matter of another application for a patent, Serial Number 673,674.

Having thus fully described our invention, 40 what we claim is—

1. The method of forming a spray nozzle which consists in supporting a bushing having a spray orifice and a breaking pin in a predetermined relation to each other, casting 45 a frame around said bushing and pin and then removing the part of the pin which which was held in the bushing.

2. The method of forming a spray nozzle which consists in supporting a bushing having a spray orifice and a breaking pin in a predetermined relation to each other, pouring liquid metal around the bushing and pin to embed them permanently in a frame, 50 and then removing the part of the pin which was held in the bushing.

In testimony whereof we affix our signatures, in presence of two witnesses.

STUART W. CRAMER.
WILLIAM B. HODGE.
